(57) **CLAIM**

The ornamental design for an audio recorder enclosure, as shown and described.

DESCRIPTION

FIG. 1 is a front perspective view of an audio recorder enclosure showing a first embodiment of the design;
FIG. 2 is a back perspective view thereof;
FIG. 3 is a front elevational view thereof;
FIG. 4 is a back elevational view thereof;
FIG. 5 is a right side elevational view thereof;
FIG. 6 is a left side elevational view thereof;
FIG. 7 is a top plan view thereof; and,
FIG. 8 is a bottom plan view thereof.
The broken lines shown in the figures are for illustrative purposes only and form no part of the claimed design.
